ELECTRIC SWITCH

Filed Sept. 6, 1928

UNITED STATES PATENT OFFICE

JOSEPH D. WOOD, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH

Application filed September 6, 1928. Serial No. 304,275.

This invention relates to electric switches and has particular reference to high tension switches which interrupt their circuit under oil.

5 When an oil immersed switch opens to interrupt its circuit, a considerable volume of oil gases and vapors is given off due to the presence of the circuit interrupting arc beneath the oil. These gases and vapors are hot 10 in their incipient state and the gases are frequently incandescent and highly conducting. It is desirable to retain these gases and vapors within the casing as far as possible since by frequent operation the level of the oil in the 15 casing may be so diminished as to render the switch inoperative. It has been found desirable, therefore, to retain these gases and vapors within the casing up to a certain elevated pressure consistent with safety, and to 20 vent them from the casing when this safe pressure is exceeded. By this expedient some of the oil gases and most of the vapors condense upon cooling and are not lost from the casing, and also a partial vacuum is not 25 formed in the casing upon cooling of the products of circuit interruption with the subsequent influx of air and the resultant condition so conducive to explosions. This arrangement, however, whereby the heated 30 gases are present in the switch casing under an elevated pressure may create a dangerous condition, for even small amounts of the heated gases escaping around the switch operating rod, while not sufficient to nullify the 35 above stated purpose, may, due to their high conductivity, cause a flash over by their presence in the vicinity of the exposed terminals. The employment of a packed gland about the switch rod is undesirable, and in 40 many cases it is necessary that the switch operating rod be permitted some latitude of movement at the point where it passes through the casing. Furthermore any frictional restraint whatever on the switch operating rod unnecessarily impedes the free 45 and rapid opening movement of the switch member which is essential in a high voltage switch.

It is therefore an object of this invention to provide a frictionless fluid sealing means

between the switch casing and the movable switch operating rod of an electric switch.

It is a further object to provide a fluid seal about a switch open rod at this point while permitting a loose running fit between the 55 rod and casing.

A further object of the invention is the provision of a spring-urged sealing member for the switch rod which also constitutes a device to accelerate the opening movement of the 60 switch.

Another object of the invention is to provide improved accelerating means for the movable switch member that acts thereon only during the first part of the switch opening 65 movement.

A still further object is generally to improve the construction and performance of oil immersed electric switches.

Fig. 1 is an elevation, partly in section, of 70 an oil immersed electric switch equipped with the fluid sealing means embodying the invention.

Fig. 2 is a detailed sectional elevation of the sealing means taken on lines 3—3 of Fig. 1. 75

Fig. 3 is a view similar to Fig. 2 with the parts in the switch open position.

Fig. 4 is a section taken along line 4—4 of Fig. 3.

The single phase electric switch herein 80 shown includes a switch frame 10 which comprises a support for the stationary and movable switch members and an oil receptacle 12 depending therebeneath. Said switch frame provides a fluid tight closure for the 85 open top of the said oil receptacle 12, and means is provided to maintain said oil receptacle yieldingly in position against said switch frame. Said means includes a yoke 14 disposed beneath said oil receptacle and tie-bolts 16 which are extended through said yoke 14 and said switch frame 10. Springs 18 are provided on said tie-bolts above said switch frame and nuts 20 serve to compress 90 springs 18 whereby to urge said receptacle 12 95 constantly into engagement with a shoulder 19 of said switch frame 10. An outer open top spill receptacle 22 is also secured dependingly to said switch frame 10. Said spill 100 receptacle is supported with its open top in

spaced relation from said switch frame 10 by means of brackets 24 which are secured removably to said switch frame by means of bolts (not shown). The stationary switch members comprise a pair of spaced insulating bushings 26 which extend through said switch frame 10 into and beneath the oil in said receptacle 12. Stationary contact members 28 are provided at the lower ends of said switch members beneath the oil in said receptacle 12.

The movable switch member comprises an insulating rod 30 which carries at its lower end a laminated brush member 32 which is adapted to engage and bridge the stationary contacts 28 in the usual manner. Said insulating brush rod 30 has at its upper end a metal switch operating rod 34, somewhat smaller in diameter, which extends loosely through an aperture 39 in said switch frame 10, (Fig. 2). The upper end of said operating rod 34 is pivotally connected at 35 to suitable switch actuating mechanism 36 by which the movable switch member is actuated between switch closed and switch open positions in the usual manner.

When the switch operates to interrupt its circuit oil gases and vapors are generated which accumulate in the gas expansion space 30 A above the level of the oil in the receptacle 12. A considerable proportion of these gases and vapors is condensable and for this reason the springs 18 which support the inner oil receptacle are sufficiently strong to maintain 35 the oil receptacle in its elevated position against the switch frame 10, whereby normally to prevent the ready escape of any material quantity of these gases and vapors from the receptacle. When, however, an abnormal pressure occurs in the receptacle, the springs 18 are adapted to yield and permit the receptacle 12 to move downwardly away from the shoulder 19 of the switch frame 10 and thus to remove the closure for the top 45 of the receptacle 12 and reduce the pressure therein to a safe value. A depending flange or apron 37 is provided on said switch frame 10 which surrounds the top of said receptacle 12 loosely, whereby to deflect the escaping oil gases and vapors and project them downwardly into the spill receptacle 22 and away from the open top thereof.

During the normal operation of the switch, substantial pressures are built up within the 50 receptacle 12 before the springs 18 are adapted to yield and, as a result, oil and conducting vapors escape around the switch rod 34 into the vicinity of live switch terminals 38.

According to the invention, means is provided to seal the aperture 39 in the switch frame 10 through which the switch operating rod 34 extends. Said means comprises, as shown particularly in Figs. 2 and 3, a cylindrical housing 40 provided with a flange 42 which is adapted to be secured beneath the

top of said switch frame 10, between the spaced ribs 44 thereof. Said switch frame 10 is provided with an annular recess 46 concentric with said aperture 39 therein and an annular flange 48 of said housing 40 is adapted to be received therein, whereby to center said housing. Bolts 50 are passed loosely through said flange 42, and are screw threaded into said switch frame 10, and serve to support said housing removably in the aforesaid position on said switch frame. Said housing 40 is provided with a bottom closure 52 having an enlarged opening 53 therein through which said switch rod 34 is loosely extended. A sleeve 54 having an annular outstanding flange 56 at its upper end is provided on said switch rod 34 with the flange 56 of said sleeve disposed within said cylindrical housing 40. Said sleeve extends loosely through said passage 53 in the bottom 52 of the housing 40 in position to engage the metal ferrule 57 on the upper end of rod 30 when the latter is in an elevated position. The inner bore of said sleeve 54 is adapted to receive said operating rod 34 so as to provide a close running fit thereabout, and adjacent faces 58 and 60 of said flange 56 and said bottom closure 52 respectively are ground to provide a fluid tight seal about the opening 53 at the bottom of said cylinder 40 when they are in engagement. An accelerating spring 62 is disposed within said housing 40 between the under face of said switch frame 10 and the upper end of said sleeve 54 above the flange 56 thereof, which spring is adapted to be compressed in the closed position of the switch, as shown in Fig. 2. A suitable bearing plate 64 is provided at the upper end of said spring 62 which is arranged to have a close wiping contact at 65 with the switch rod 34, and which is free for lateral movement in said housing 40.

When the switch is released for opening movement, the accelerating spring 62 acts upon the switch rod 30 through the medium of said sleeve 54 to give an initial impetus to the switch opening movement of the movable switch member. When the flange 56 of the sleeve 54 has moved a sufficient distance to engage the face 60 of the housing 40, as shown in Fig. 3, the remaining tension of the spring 62 serves to maintain the cooperating ground surfaces 58 and 60 firmly in engagement, whereby to provide a fluid tight seal about the aperture 53 in the bottom of said housing 40. During the remainder of the switch opening movement the sleeve 54 remains in this position so that before an elevated pressure is developed in the receptacle due to the presence of the circuit interrupting arc in the oil, the fluid tight seal is completed about the switch rod 34, without imposing any restraint on the movable switch member as is the case with the usual gland and packing construction. The switch rod 34

is free at all times for slight lateral movement in the aperture 39 of the switch frame and the aligned aperture 53 in the housing 40, whereby slight inaccuracies in the switch 5 actuating mechanism will not cause the rod to bind. The relative strengths of the tank supporting springs 18 and the accelerating spring 62 are such that the pressure acting upwardly on the sleeve 54 will never be sufficient to raise the flange 56 off its seat 60 before the springs 18 will have permitted the receptacle 12 to descend and relieve the pressure within the receptacle. Consequently, under no condition can oil escape around the 10 switch rod 34 into the vicinity of the switch terminals 38 but it will always be projected downwardly past the apron 37 into the outer 15 spill receptacle 22.

The construction may be modified in many respects without departing from the scope of the invention.

I claim:

1. In an electric switch, the combination of an enclosing casing adapted to contain oil, a switch operating rod extended through an aperture in one wall thereof, and means movable into and of sealing relation with said aperture having an operative connection with said switch operating rod arranged to be moved into sealing relation with the aperture during the switch opening movement of said switch operating rod.

2. In an electric switch having an enclosing casing adapted to contain oil and having stationary and movable contact members disposed therein beneath the oil, the combination of a switch operating rod extended freely through an aperture in a wall of said casing and connected operatively with said movable contact member, an accelerating spring disposed about said rod, and sealing means for said aperture associated with said rod to compress said spring and uncover said aperture in the closed position of the switch and to cover said aperture in the open position of the switch.

3. In an electric switch the combination of an enclosing casing adapted to contain oil, a switch operating rod extended through an aperture in a wall of said casing and axially movable therein between switch open and closed positions, said rod being loosely received in the aperture in said casing wall whereby to permit a substantial lateral movement thereof in said casing, and accelerating means for said switch operating rod, said accelerating means including a sleeve engageable with and having a close running fit on said rod in said aperture and having provision for effecting a fluid tight seal of said aperture when the switch is open.

4. In an electric switch, the combination of an enclosing casing adapted to contain oil and having an opening in a wall thereof above the normal level of the oil, a housing

secured in fluid tight relation to said casing over the opening therein, said housing having an opening therein aligned with and spaced from the opening in said casing, a switch operating rod having a reduced upper metal portion loosely received in the aligned openings in said casing and housing and a lower enlarged insulating portion disposed beneath said housing extended into the oil in said casing, and means carried by the upper portion of said rod and loosely disposed in said housing and extended through the opening therein to engage the lower insulating portion of said rod arranged to cooperate with said housing to provide a fluid tight seal between said rod and housing in the vicinity of the opening therein.

5. In an electric switch, the combination of an enclosing casing adapted to contain oil, and having an aperture in a wall thereof above the level of the oil, a housing secured in fluid tight relation to said wall about said aperture and above the oil in the casing, said housing having an aperture spaced from and aligned with the aperture in said casing wall, a switch operating rod extended into said casing through said housing and received loosely in said aligned apertures, an accelerating spring carried by said rod and disposed within said housing between said spaced apertures, and a sleeve carried loosely by said rod arranged to compress said spring when said rod is moved to switch closed position, said sleeve being biased by said spring in the switch open position of said operating rod into a position to seal the passage through said housing at the aperture therein.

6. In an electric switch, the combination of an enclosing casing adapted to contain oil and having a gas expansion space above the oil, said casing having an aperture in a wall thereof in communication with said gas expansion space, an open-top housing disposed within said casing having its open top secured in fluid tight relation to and surrounding the aperture in said casing wall, said housing having an aperture in its bottom wall aligned with the aperture in said casing wall, a switch operating rod extended loosely through the aligned apertures in said casing and housing, a sleeve closely surrounding and slidable on said operating rod and extended loosely through the aperture in said housing, said sleeve having an outstanding flange disposed within said housing and arranged to engage the lower wall of said housing to provide a fluid tight seal about the aperture therein, and resilient means disposed within said housing to bias said sleeve into sealing engagement with said housing.

7. In an electric switch, the combination of an enclosing casing adapted to contain oil and having a gas expansion space above the oil, said casing having an aperture in a wall thereof in communication with said gas ex-

- pansion space, an open-top housing disposed within said casing having its open top secured in fluid tight relation to and surrounding the aperture in said casing wall, said housing having an aperture in its bottom wall aligned with the aperture in said casing wall, a switch operating rod extended loosely through the aligned apertures in said casing and housing, a sleeve closely surrounding and slidable on said operating rod and extended loosely through an aperture in said housing, said sleeve having an outstanding flange disposed within said housing and arranged to engage the lower wall of said housing to provide a fluid tight seal about the aperture therein, and resilient means disposed within said housing to bias said sleeve into sealing engagement with said housing, and an abutment on said rod arranged to engage and move said sleeve upwardly on said rod against the bias of said spring in the switch closed position of said switch operating rod.
8. In an electric switch, the combination of an oil-containing enclosing casing, contacts separable within said casing, an operating rod for said contacts extended into said casing through an opening therein, a valve member for closing said opening having means engaged by said rod for moving it away from said opening, and other means operable when said valve member is disengaged from said rod for moving said valve member toward said opening.
9. In an electric switch, the combination of an oil-containing casing, separable contacts enclosed therein, operating mechanism for said contacts including an operating rod movable in the direction of its length through an aperture in said casing, a long sleeve slidable on said rod having an enlarged head which can seat on said casing over said aperture to seal it, said rod having a step which engages said sleeve to move it away from said aperture when said rod is moved in one direction, and a spring bearing on said sleeve to move it in the opposite direction into sealing relation with said aperture, said spring also acting through said sleeve to move said rod.
10. In an electric switch, the combination of a casing having a wall provided with a rod-opening, a housing secured to said wall about said opening and having an opening in one end aligned with said wall opening a switch rod passed through said wall opening and housing, a valve member slidable on said rod, and a spring located in said housing urging said valve member against said housing-opening, said rod having means to move said valve member away from said opening.
11. In an electric switch, a wall having an opening, a housing secured to said wall about said opening and having an opening in the end thereof aligned with said wall opening, a switch operating rod extended through
- said openings, a sleeve slidable on said rod in said housing-opening having an outstanding flange in said housing which overlies said housing-opening, a spring for holding said flange on said rod over its opening, and an abutment on said rod which engages said sleeve and moves said flange away from said housing-opening.
12. In an electric switch, stationary and movable switch members, said movable switch member having a lifting rod, means providing a pair of fixed abutments which are disposed adjacent and are spaced axially of said rod, a spring located between said abutments and bearing against one of them, a sleeve axially loose on said rod against which said spring bears and having an outstanding part which overlies said other abutment and is held thereagainst by said spring, said rod having an abutment which is engageable with and can move said sleeve toward said other abutment, said rod being free for a predetermined extent of movement independent of said sleeve.
13. In an electric switch, a wall having a chamber with aligned openings at the outer and inner ends thereof, a switch operating rod extended through said openings, a helical compression spring located within said chamber surrounding said rod and normally held in a partially stressed condition by the ends of said chamber, and means operative in response to switch closing movement of said rod for further compressing said spring.
14. In an electric switch, an enclosing casing having an opening in a wall thereof, a housing secured to said casing having openings in its opposite end walls which are aligned with said casing opening, a switch operating rod extended through the aligned openings of said casing and housing, a compression spring surrounding said rod in said housing which is held in a partially stressed condition between said casing and housing walls, and means operative in response to switch closing movement of said rod for further compressing said spring.
15. In an electric switch, an enclosing casing having an opening in a wall thereof, a housing secured to said casing having openings in its opposite end walls which are aligned with said casing opening, a switch operating rod extended through the aligned openings of said casing and housing, a compression spring surrounding said rod in said housing which is held in a partially stressed condition between said casing and housing walls, and means operative in response to switch closing movement of said rod for further compressing said spring, said means including an operating member carried by and having a lost motion connection with said rod, and an abutment on said rod arranged to engage said operating member

only in the final switch closing movement of said rod.

- 5 16. In an electric switch, a wall having an opening, a housing secured to said wall about said opening having an opening in the end thereof which is aligned with said wall opening, a switch operating rod extended through said openings, a sleeve slidable on said rod in said housing-opening having an outstanding flange located in said housing which overlies said housing-opening, a stressed spring located in said housing for holding said flange on said housing over its opening, switch operating mechanism for reciprocating said rod between a switch open and a switch closed position, and means to further compress said spring upon movement of the rod to switch closed position including an abutment on said rod which engages and actuates said sleeve 10 20 in the final switch closing movement of said rod.

17. In an electric switch, a casing wall having an opening, a housing secured to said wall about said opening having an opening in the end thereof which is aligned with said wall opening, a switch operating rod extended loosely through said openings having an enlarged lower portion and a reduced upper portion which is located within said housing, a sleeve slidably carried by the upper portion of said rod and extended loosely through and having its lower end terminate beyond the opening in said housing, said sleeve having an outstanding flange at its other end which 35 is within said housing and which overlies said housing-opening, a helical spring located in said housing surrounding said rod and holding said flange against said housing over its opening, switch operating mechanism 40 for reciprocating said switch operating rod between a switch closed position in which the lower end of said sleeve is engaged by and is moved upwardly against the action of said spring by the enlarged lower portion of said 45 rod, and a switch open position in which said flange is held over said housing opening by said spring and the enlarged lower portion of said rod is moved out of engagement with and below the lower end of said sleeve.

- 50 18. In an electric switch, the combination of a horizontal casing wall having an opening, a vertically disposed switch operating rod having a lower enlarged portion and an upper reduced portion which is extended in said casing opening, a helical compression spring encircling the reduced portion of said rod beneath said casing wall, a sleeve slidable on the reduced upper portion of said rod between said spring and the enlarged portion 55 of said rod, said sleeve adapted to compress said spring upon upward movement of the rod into switch closed position, and means to arrest the downward movement of said sleeve upon downward movement of said operating rod at a point at 60 65

which said spring is still in a condition of stress.

19. In an electric switch, the combination of a casing wall having an opening, a switch operating rod extended through said opening and having an abutment thereon which is spaced from said casing wall, a helical compression spring surrounding said rod between said wall and abutment, said abutment arranged in the switch closed position of said rod to compress said spring whereby to store up energy for a subsequent opening movement of the rod, and means including a housing disposed about said spring for limiting the recoil of said spring upon switch opening movement of said rod.

20. In an electric switch, the combination of a casing wall having an opening, a switch operating rod having a lower enlarged portion and an upper reduced portion which is extended in said casing opening, a helical compression spring encircling the reduced portion of said switch operating rod which in the switch closed position of said rod is compressed between the enlarged portion of said rod and said casing wall, the enlarged portion of said rod being free from engagement with said spring in the switch open position thereof, and means including a casing surrounding said spring to restrict the recoil thereof upon opening the switch whereby to maintain said spring always under stress irrespective of the position of said rod.

In testimony whereof, I have signed my name to this specification.

JOSEPH D. WOOD.
